UNITED STATES PATENT OFFICE.

WILLIAM FISCHER, OF WATERTOWN, NEW YORK.

FIRE-ESCAPE.

SPECIFICATION forming part of Letters Patent No. 595,453, dated December 14, 1897.

Application filed May 14, 1897. Serial No. 636,494. (No model.)

To all whom it may concern:

Be it known that I, WILLIAM FISCHER, of Watertown, in the county of Jefferson and State of New York, have invented certain new and useful Improvements in Fire-Escapes; and I do hereby declare the following to be a full, clear, and exact description of the invention, such as will enable others skilled in the art to which it appertains to make and use the same.

My invention relates to certain new and useful improvements in fire-escapes of the extensible-ladder type, and has for its object to provide, in a device of this character, an improved construction of suspending means for normally supporting the fire-escape when out of use and an improved construction of extensible-ladder escape, all of which will be hereinafter more fully described, and specifically set forth in the appended claims.

In the accompanying drawings, illustrating the invention, Figure 1 is a perspective view showing my invention extended for use. Fig. 2 is a perspective view showing the fire-escape folded and removed from its casing. Fig. 3 is a horizontal section of the fire-escape and casing. Fig. 4 shows a front view of one of the collapsible sections, and Fig. 5 is a view of one of the metallic hangers.

Like numerals designate corresponding parts throughout the several figures of the drawings.

Referring now more particularly to the drawings, the numeral 1 designates a portion of a window-sill, and 2 a box or casing in which the fire-escape is inclosed when not in use, said casing in practice resting upon the floor adjacent the window.

My improved fire-escape consists of a top section 3 and a bottom section 4 and a series of intermediate collapsible sections 5. The upper section consists of two side bars 6, connected at the top by a cross-bar or round 7, and provided on the face side thereof with a longitudinally-extending tongue 8.

On the rear side of each bar 6 of the upper section are keepers 9, in which are confined hangers or grapple-irons 10, each having a laterally and inwardly projecting grapple-iron 11, adapted to rest upon the window-sill, and provided with a downturned extremity 12, adapted to take on the inside of the sill

and retain the irons in position. The lower ends of these irons are formed with substantially S-shaped hooks 13, which serve as stops 55 to support the upper section of the fire-escape and limit the downward movement thereof.

The lower section 4 is constructed substantially the same as the upper section, except that it is provided with two base blocks or 60 boards 14, which are adapted when the device is in use to rest upon the ground and when it is not in use to support the intermediate sections. The said bars of the lower section are provided on their inner or rear 65 faces with longitudinal grooves or guideways 15.

The intermediate sections 5 are each provided on their faces or front sides with tongues 17 and on their rear sides with grooves or 70 guideways 18, the said tongues and guideways being adapted to engage with the guideways or tongues on the next adjoining section, as will be readily understood. Each section is also provided at top and bottom at 75 its inner edges with stop-blocks 20, which are adapted to abut against one another to limit the extension movement of the sections, and each section is also provided at the lower end thereof with a stop-plate 21, extending across 80 the groove guideway thereof to prevent separation of the sections. The intermediate sections, as well as the lower section, are provided with cross-bars or rounds 7, which connect the side bars thereof. 85

The operation is as follows: Normally—that is, when the device is out of use—the sections are folded, as shown in Fig. 2, and are inclosed within the box or casing 2. When the fire-escape is to be used, it is lifted from its 90 casing and the grapple-irons are placed in position upon the window-sill. The lower section 4 is then released and with the intermediate sections permitted to drop by gravity, the said sections moving on each other until 95 the lower section reaches the ground. The several sections will thereby form a ladder reaching from the window-sill to the ground, by which the inmates of the building may escape. When the sections are extended, the 100 rounds 7 thereof form a complete ladder, by which the inmates of the building may descend from the upper floors to the ground.

Having thus described my invention, what

I claim as new, and desire to secure by Letters Patent, is—

1. In a fire-escape, the combination of a series of extensible sections provided with 5 tongue-and-groove connections and movable on one another, and each section also provided at top and bottom with stop devices adapted to abut against corresponding stop devices on the adjoining sections to limit the 10 movement thereof, base-blocks on the lower section adapted to rest upon the ground and grapple-irons swiveled in keepers on the upper section and having their upper ends bent to form grapples adapted to rest upon the 15 window-sill and their lower ends provided with hooks forming stops adapted to abut against the keepers, substantially as described.
2. In fire-escapes, the combination of top 20 and bottom sections, the former provided at the rear side thereof with pivoted grappling-

irons adapted to engage the window-sill and the latter having at its lower ends base-blocks adapted to rest upon the ground when the device is extended and a series of intermediate 25 extensible sections each provided at one side with tongues and at the opposite side with grooves, said tongues and grooves being adapted to engage with corresponding grooves and tongues on the adjoining sections, and 30 each section also being provided with stop-blocks and stop-plates at the lower end of their grooved guideways, substantially as described.

In testimony whereof I have signed this 35 specification in the presence of two subscribing witnesses.

WILLIAM FISCHER.
